THREADED AND REVERSIBLE STANDING-VALVE SOCKET.

Application filed December 10, 1925. Serial No. 74,636.

Although my present invention is entitled as referring to a standing valve seat, it should be understood that this invention relates also to fittings cooperating with said seat, and to organizations in which said seat and said fittings are employed.

The standing valve or foot valve as used in pumping oil wells, is the bottom valve on a string of tubing. It will be understood that this valve does not bodily move up and down with pump plunger. Oil passes upward through the standing valve because said valve has a "floating" member, either ball or plumb bob, which rises off its seat when pressure below said "floating member" is in excess of pressure on top of said "floating member", as when pump plunger, which is above said standing valve, is on its upward stroke. The "floating member", ball or plumb bob, returns downward to its seat in standing valve as plunger of pump reaches end of upward stroke and ceases its attempt to create suction on standing valve. A standing valve "floating member", which for brevity I elect to call a ball, returns to its seat in standing valve, thus trapping all oil above it. The hollow pump plunger, with a very similar valve placed optionally on top or bottom of plunger, and sometimes at both top and bottom of plunger, continues its downward course forcing the trapped oil through the plunger valves.

The standing valve ball and seat have heretofore been enclosed in a chamber. The top part thereof called the cage, limits and controls the upward flight of the ball and its return to its seat. The lower part, to which the cage is attached, is called the standing valve body; and its upper end contains or retains the seat for the ball. The lower end of this standing valve body, externally, is tapered approximately $7\frac{1}{2}^{\circ}$ and forms a wedged contact with an outer cylindrical body called the standing valve shoe. This standing valve shoe for $2\frac{1}{2}''$ pump has been approximately $5''$ to $9''$ long, internally, its lower end has the tapered seat into which the lower end of the standing valve body, tapered externally, fits. Below this tapered seat the standing valve shoe has had sufficient length to take the threaded end of oil tubing.

Above this tapered seat a standing valve

shoe of the old type must have sufficient length to contain the standing valve body (ball and seat and cage with flight chamber for ball) and sufficient additional length to take the threaded end of a tubing nipple to connect the standing valve shoe with the bottom of a pump barrel. The standing valve complete has been inserted through large upper end of standing valve shoe to rest in the tapered seat at the bottom of the shoe.

As the vertical column of oil supported by the standing valve in some cases approximates a mile in length or height and the downward thrust of the plunger adds a tremendous pressure against the taper fit between the standing valve body and the standing valve shoe, said tapered fit should be as near perfect as possible or oil will leak past said tapered fit and lessen the efficiency of the pump; but standing valve shoes have customarily been made in one piece $5''$ to $9''$ long, with the tapered fit at lower end, seat upward. In perfecting these, a mechanic must reach a cutting tool through the large end of the shoe,—with the cutting edge of the tool a relatively long distance from its support and largely out of sight, and thus fashion the tapered seat. Needless to say, many standing valves leak.

In my invention, the tapered seat is a separate piece from the shoe and is removable. The tapered seat extends to the very top end of this separate piece. The cutting edge of any forming tool used in the perfecting of the same can be backed up closely by a tool support,—tending to lessen the "chatter" of the cutting edge; and the tapered surface is in plain sight of the operator during cutting and testing for accuracy,—whereas in the old form the tapered seat was relatively near the bottom of a tube, difficult to reach and form perfectly, difficult to test as to accuracy, and difficult to reseat in the oilfield when it becomes worn and leaks. When the old style tapered seat has been repaired a few times, the metal has been cut away to such an extent that the whole standing valve shoe must be thrown away.

In my invention, when the replaceable removable tapered seat has gone beyond repair, it alone is thrown away and its retaining parts are as good as new to enclose another

replaceable tapered seat. In my invention the tapered seat may be of bronze, to obviate the destructive acids which, in some wells, pit and eat the seat so that it leaks.

5 My replaceable tapered seats may be made of, for example, a suitable acid-resisting steel, which has proven a success in resisting said destructive acids—while the seat container may be made of suitable but cheaper 10 steel; or my replaceable seats may have inserted or cast babbitt cores, into which the lower ends of standing valve bodies may be pounded or forced; or my replaceable tapered seats may be made of ordinary steel 15 and hardened and ground to a more perfect fit than is possible in the case of older standing valve shoes.

With my replaceable seats I may use two-part shoes. The outer cylindrical surface of 20 tapered seats is threaded. Approximately one half its length screwed into the upper half or part of a sectional standing valve shoe, and the other half, approximately, of its length is screwed into the other half or 25 part of the standing valve shoe. The upper and lower halves or parts of the shoe may jam together on the thread of the replaceable taper seat, and make an oil tight joint of lock nut effect.

30 It being now a common practice to provide, for use in deep wells, means whereby a standing valve may be inserted or withdrawn through a pump barrel—in order to obviate the lifting of an entire tubing string when- 35 ever the standing valve ceases to operate satisfactorily—it is an object of this invention to provide an improved seat or socket and improved fittings, constituting the mentioned sectional shoe for association therewith; and 40 preferred embodiments of my invention may comprise not only a seat or socket and threaded fittings, but parts (which may be substantially identical with one another and interchangeable in position of use) adapted re- 45 spectively to connect a pump barrel and a perforated tube or leg, or the like, therewith; and preferred embodiments of my invention may comprise socket elements which are adapted to serve, in the indicated manner, as 50 interior couplings, and which are nevertheless symmetrical with reference to either a central vertical line or with reference to a horizontal plane,—each socket element being pro- 55 vided with a pair of oppositely disposed conical faces, for alternative or sequential use; and the described parts may be adapted to co- 60 operate with a removable standing valve organization comprising means for the support of a so-called gas-anchor pipe, extending 65 through said socket and to a level below the lowermost apertures in a perforated tube or leg; and, when dependent, the said leg may be supported, directly or indirectly, by or through said socket element. The mentioned 70 gas anchor may be used either to exclude gas

or as an aid in holding the standing valve body in its seat, or for both of these effects.

Other objects of my invention may be best appreciated from the following description of an illustrative embodiment thereof, taken in connection with the appended claims and the accompanying drawings, in which

70 Fig. 1 is, for the most part, a median vertical section, parts being broken away.

Fig. 2 is an enlarged separate view, taken 75 in the same plane as Fig. 1, but showing an alternative type of socket element, in which Babbitt linings are employed.

Referring to the details of that specific embodiment of my invention chosen for purposes of illustration, 11 may be a pump barrel or cylinder of any usual or preferred type, with or without a special lining, and 12 may be a perforated tube or leg secured therebelow by means comprising an externally 80 threaded socket element 13, sections of the continuous external thread 14 thereon being shown as respectively engaged by interior threads upon interchangeable complementary coupling elements 15 and 16, which 85 may be regarded as together constituting a two-part standing valve shoe. The former of these parts or couplings is shown as provided with an interior thread 17, to receive a corresponding thread upon the lower end of 90 the pump barrel 11, and the latter is shown as provided with an interior thread 18, engaged by a correspondingly threaded portion of the 95 perforated leg 12.

The socket element 13 is shown as provided with oppositely tapering conical faces 19 and 20, either of which, according to the manner in which said socket element is disposed, is suitable to receive a correspondingly tapered hollow plug 21, suitable for the retention of a standing valve organization 100 of any preferred character,—as, for example, a standing valve organization including, in addition to the mentioned parts, a connecting and seat-carrying element 22, a plumb-bob or other valve 23, a cage 24, and an engageable upward projection 25. The hollow plug 21, or its equivalent, may, if desired, be provided, at or near its lower end, with an internal thread 26, adapted to receive a correspondingly threaded end of a so-called gas-anchor 27,—the lower end of 105 which may terminate, as within a bull-nose 28 retained by a coupling 29, below the lowermost inlet openings 30 in the perforated leg 12, or its equivalent.

110 By constructing my socket elements as separate articles adapted to cooperate with associated parts in the described manner, preferably using in connection therewith interchangeable coupling elements of the described character, I not only simplify standing valve retaining organizations but provide for the easier and more accurate finishing 115 of the essential parts; and I also notably 120

- prolong the period of service of each socket element and facilitate the restoration or replacement thereof. The principles of my invention are favorable to easy assembly or disassembly, affording quick access to any one of several parts by the unscrewing of one or two threaded connections; and, although I may form my socket elements, as well as the associated parts, from a suitable steel, the described construction is entirely favorable to the use of a brass or a special composition in the casting of special socket elements; and I may even use Babbitt metal as a lining for socket elements of the general character described (preferably providing special depressions for the reception of the babbitt, somewhat as suggested in Fig. 2)—it being however necessary that the body of the socket elements have sufficient tensile strength to adapt the same to cooperate with steel or other couplings in securing the mentioned parts in their assembled relationships. In Fig. 2, I suggest the cutting of annular grooves 31^a in a socket element 13^a and the drilling of radial depressions 32^a at suitable intervals along one or more of the mentioned grooves,—these grooves and depressions, or equivalent irregularities, being suitable to the retention of Babbitt linings 33^a, which may be cast in place and subsequently cut or otherwise finished to provide a smooth surface having a desired taper; and the interiors of all my socket elements are easily accessible for initial or restorative cutting or grinding.
- Although I have herein described a single complete embodiment of my invention, suggesting alternative details, it should be understood not only that various features thereof may be independently used but also that numerous modifications might be made by those skilled in the art to which this case relates, without the slightest departure from the spirit and scope of this invention, as the same is indicated above and in the following claims.
- I claim as my invention:
1. In an organization of the general character described: a downwardly tapered standing valve body; a socket element provided with a plurality of similar oppositely disposed and correspondingly tapered faces for alternative use, to provide a wedge fit and removably to retain said tapered body.
  2. In an organization of the general character described: a seat for a standing valve body, which seat has the form of a socket element provided with a plurality of oppositely disposed tapered faces formed in substantially flat unobstructed surfaces for alternative use in a wedge-fitting relationship with said body, said socket element being of substantially uniform external diameter, except as it is provided with threads adapting the same to serve as a coupling element.
  3. A socket element for a standing valve body interiorly provided with oppositely disposed conical faces formed in substantially flat unobstructed surfaces tapered suitably to effect a wedge fit with said body, said element being externally provided with a continuous thread, and both ends of said element being substantially alike, to render the same interchangeable in use.
  4. In combination: a socket element as described in claim 3; and interchangeable symmetrical coupling members, internally threaded at both ends respectively, each of said members engaging portions of said socket element thread.
  5. In combination: a socket element as described in claim 3; a standing valve organization comprising a tapered body; a pump barrel extending above said body and interchangeable symmetrical coupling members internally threaded at both ends respectively engaging portions of said socket element thread, one of said coupling members being engaged by said pump barrel.
  6. In combination: a socket element as described in claim 3; a standing valve organization comprising a tapered body; a pump barrel extending above said body and interchangeable symmetrical coupling members internally threaded at both ends respectively engaging portions of said socket element thread, one of said coupling members being engaged by a pump barrel, and another of said coupling members being provided with means for the support of a perforated leg.
  7. In combination: a socket element as described in claim 3; a pump barrel thereabove; a perforated leg therebelow and interchangeable symmetrical coupling members internally threaded at both ends respectively engaging portions of said socket element thread, one of said coupling members being engaged by said pump barrel, another of said coupling members being provided with means for the support of said perforated leg; and a standing valve organization, removably seated within said socket element and comprising a gas anchor extending into said perforated leg.
  8. In combination: a socket element as described in claim 3 which is provided with oppositely tapered inner linings of a non-ferrous material.
  9. In an organization of the general character described; a reversible socket element for the reception of a standing valve body, said element being provided with means for its retention between substantially identical coupling elements; oppositely disposed coupling elements abutting end to end and respectively engaged thereby and cooperating to produce a lock-nut effect; and a standing valve organization removably supported by said socket element.
  10. In an organization of the general char-

acter described: a sectional standing valve shoe comprising interchangeable parts; a standing valve body movably retaining therein and comprising a seat, a cage and a valve which is movable relatively to said seat; and a replaceable and reversible seat element of substantially uniform diameter to

receive said body, said seat engaging the respective parts of said shoe.

In testimony whereof, I have hereunto set my hand at Los Angles, California, this 3rd day of December, 1925.

SUMNER B. SARGENT.
